DESIGN FOR A CUP OR SIMILAR ARTICLE

Sidney E. Thompson, West Englewood, N. J.

Application April 8, 1936, Serial No. 62,008

Term of patent 14 years

To all whom it may concern:

Be it known that I, Sidney E. Thompson, a citizen of the United States and a resident of West Englewood, in the county of Bergen and State of New Jersey, have invented a new, original, and ornamental Design for a Cup or Similar Article, of which the following is a specification, reference being had to the accompanying drawing, forming part thereof.

The characteristic feature of the design is the handle shown in full lines.

I claim:

The ornamental design for a cup or similar article as shown and described.

SIDNEY E. THOMPSON.
